UNITED STATES PATENT OFFICE.

WILLIAM H. DRUMMOND, OF BELLEVILLE, NEW JERSEY, ASSIGNOR OF ONE-HALF
TO ELWOOD JONES, OF NUTLEY, NEW JERSEY.

ACOUSTICAL DIAPHRAGM.

Application filed October 30, 1917. Serial No. 199,227.

To all whom it may concern:

Be it known that I, WILLIAM H. DRUMMOND, a citizen of the United States, and resident of Belleville, county of Essex, State 5 of New Jersey, have invented certain new and useful Improvements in Acoustical Diaphragms, of which the following is a specification.

The present invention relates to the utilization of the inner skin of trees, such as that of the poplar tree, the basswood tree, the tulip wood tree and that of such other trees and vegetable growth as may be found useful for the present purpose, and the production of an article of any desired thickness for use in the arts.

I have found that the inner skin of the poplar tree, for instance, when subjected to moisture disintegrates into very fine films 20 having strength enough to permit of their being handled. When washed and dried, an article is produced having considerable strength and useful in making diaphragms for sound boxes of phonographs and microphones. The material also can be used in the manufacture of musical instruments, such as violin cases, horns, as for phonographs, organ pipes, sound boards of any 25 description, because of its excellent resonant qualities. From its nature, the material is a non-conductor and is useful, therefore, as a dielectric in the electrical art.

The surface of the article when finished has a pleasing figure, and the material can 35 be used in making of art objects and for decorating purposes. The material is more or less translucent, regulated by the thickness of the finished article and is useful as a lamp shade, for instance.

The material can be worked in the way 40 that wood is worked, and utilized in the making of articles, such as boxes, cases and receptacles, generally.

In the assembling of the articles for any 45 desired purpose, any suitable means for supporting a layer or for binding layers together is used, such, for instance, as glue or shellac or collodion.

The use of the above material as a substitute for the mica or metal diaphragms in the sound boxes of phonographs and the like 50 has given remarkable results, the tonal qualities of the records being accurately repro-

duced, and the needle scratching being greatly reduced or eliminated altogether.

I have, therefore, illustrated my invention as applied to the manufacture of diaphragms for sound boxes in the accompanying drawing, in which Figure 1 is a surface elevation of a diaphragm; Figure 2 is a side view of the diaphragm; Figure 3 is a disk of stiffening or supporting material; Figure 4 is a side view of a diaphragm composed of one of each of the materials shown in Figures 1 and 3; and Figure 5 is an enlarged side view of a diaphragm when the stiffening material is used as a core.

Referring to the drawings, (Fig. 1) 1 is a film of the inner skin of the poplar tree and 2 is another film (Fig. 2), the two layers 70 being joined together by glue, or shellac. While I have shown in Figure 2 only two layers of material, it is to be understood that the number of layers will be multiplied, if desired, until an article of the desired thickness is obtained.

The strength of the material is increased if the grains of the films are crossed, in the assembling of the diaphragm.

For the purpose of further strengthening 80 the diaphragm, a supporting or stiffening material, such as linen, silk, cotton, wire-cloth or, a sheet of thin metal, perforated, if desired, shown at 3 (Fig. 3) is used and faced with one or more layers of film, 1 (Fig. 85 4). Here again, the grains of the films, 1, are crossed when the additional strength of that arrangement is desired.

The preferred form of diaphragm is shown in Figure 5, where the supporting 90 material, 3, is shown faced on both sides with a layer of film 1 and 2. Other layers, 1^a or 2^a are added to one side or to both sides to obtain any desired thickness. In 95 this embodiment, as in the others, the grains of the films may be crossed with respect to each other for obtaining additional strength.

If desired, the outer surfaces of the material are coated with shellac for rendering 100 the article moisture proof. In the stamping out of the article for use as diaphragms for phonograph sound boxes, I have found it advantageous to use polished dies, heated prior to the punching operation and at each 105 punching operation to leave the die down

and then cool off the die before raising it from the article. This alternate heating and cooling operation is repeated for each disk. When this is done, the article has a highly polished surface or surfaces

5 I claim as my invention:

1. A diaphragm for sound boxes composed of superposed washed natural films of vegetable growth.
- 10 2. A diaphragm for sound boxes composed of a washed natural film of vegetable growth and a layer of strengthening material.
- 15 3. A diaphragm for sound boxes composed of washed natural films of vegetable growth and an interposed layer of strengthening material.
- 20 4. A diaphragm for sound boxes composed of superposed washed natural films of vegetable growth and crossed as to their grain.
- 25 5. A diaphragm for sound boxes comprising superposed washed films of the inner skin of the poplar tree in their natural state.
- 26 6. A diaphragm for phonographs com-

prising superposed washed films of the inner skin of the poplar tree in their natural state and a layer of woven fabric.

7. A diaphragm for phonographs comprising superposed washed films of the inner skin of the poplar tree in their natural state and an interposed layer of woven fabric.

8. A diaphragm for sound boxes comprising superposed washed films of the inner bark of the poplar tree in their natural state and an interposed layer of woven fabric and a binding material.

9. An acoustic diaphragm composed of washed natural films of vegetable growth.

10. An acoustic diaphragm composed of washed natural films of vegetable growth artificially joined in a unitary structure.

Signed at New York in the county of New York and State of New York this 29th day of October A. D. 1917.

WILLIAM H. DRUMMOND.
